UNITED STATES PATENT OFFICE.

JACOB W. BERKOF, OF NEW YORK, N. Y.

DESIGN FOR A TOY POODLE-DOG.

42,498.

Specification for Design.

Patented May 14, 1912.

Application filed December 30, 1911. Serial No. 668,773. Term of patent 7 years.

To all whom it may concern:

Be it known that I, JACOB W. BERKOF, a citizen of the United States, and a resident of the city of New York, borough of Brooklyn, in the county of Kings and State of New York, have invented a new, original, and ornamental Design for a Toy Poodle-Dog.

Reference is to be had to the accompanying drawing, in which the figure is a perspective view of a toy poodle dog.

I claim:

The ornamental design for a toy poodle dog, as shown.

JACOB W. BERKOF.

Witnesses:

W. S. ORTON,

PHILIP D. ROLLHAUS.
